ATTORNEY

UNITED STATES PATENT OFFICE.

HENRY N. WADE, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTROMAGNETIC SWITCH.

Application filed August 7, 1919. Serial No. 315,803.

This invention relates to electromagnetic switches responsive to undulating currents.

In practice there are instances where a switch responsive at a given frequency of the current supplied thereto but unresponsive at other frequencies of such current would be extremely advantageous and the present invention has among its objects to provide an efficient and reliable switch to so function.

Another object is to provide a switch which may be readily designed and adjusted to respond at a given frequency of the current supplied thereto and to be unresponsive at all higher frequencies.

Other objects and advantages of the invention will hereinafter appear.

The accompanying drawing illustrates one embodiment of the invention which will now be described, it being understood that the embodiment illustrated is susceptible of various modifications without departing from the scope of the appended claims.

In the drawing,

Figure 1 is a side view of the switch, and Fig. 2 is a front view thereof.

The switch illustrated comprises a contact arm 1 of magnetic material co-operable with a stationary contact 2, said arm being pivotally supported on a magnet frame 3 which carries a winding 4 to effect attraction of said arm and a coil 5 to function as hereinafter set forth. The magnet frame and stationary contact are fixed to an insulating support 6 and a spring 7 is connected at one end to the contact arm 1 and at its other end to a member 8 adjustably secured to the base to normally disengage said arm from the stationary contact.

The magnet frame has parallel pole pieces 9, 10 and 11 the pole pieces 10 and 11 being formed integrally therewith. The intermediate pole piece 10 which is rectangular in cross section forms a supporting core for the winding 4 and also serves to pivotally support the contact arm, said pole piece having its end bifurcated to receive a block 12 fixed to said arm and carrying a pin 13 passing through said block. The pole piece 9 is cylindrical and forms a supporting core for coil 5, the latter preferably comprising a plurality of copper washers of varying thickness. This pole piece is mounted on a threaded stud 14 projecting through the magnet frame and base and the washers 5

are detachably secured thereon by screws 15 threading into the magnet frame. The pole piece 11 which as best shown in Fig. 2 is V-shaped in cross section, serves as a stop for the lower end of the contact arm 1, said arm carrying an adjustable non-magnetic set screw 16 to engage said pole piece.

It will thus be observed that the magnetic flux of the winding 4 has parallel paths through the pole pieces 9 and 11 respectively, whereby it produces actuating and lockout pulls on the contact member, the arrangement being such that the actuating pull preponderates the lockout pull except as hereinafter set forth. Further it will be observed that if the winding 4 is supplied with an alternating, pulsating or other undulating current its magnetic flux which threads the coil 5 will induce currents in the latter varying with the frequency of the current supplied to said winding 4, whereby coil 5 will function as a damping coil to oppose the magnetic flux tending to attract the arm 1. Thus the coil 5 will cause a part of the flux to traverse the aforesaid parallel path through pole piece 11, the percentage of flux traversing this path varying with the damping currents induced in coil 5. The opposing effect of coil 5 as is well understood will increase with an increase in frequency of the current supplied to winding 4 and will decrease with a decrease in the frequency of such current whereby a maximum percentage of flux will be caused to traverse the pole piece 11 at maximum frequency, while a minimum percentage of flux will be caused to traverse said pole piece at minimum frequency. Obviously, therefore, the switch will tend to respond at a certain frequency and to lock out at all higher frequencies.

The switch illustrated may be adjusted in various ways for variation of its sensitiveness through wide range. For example, the sensitiveness of the switch may be varied by varying the size of coil 5 or by relative variation of the air gaps between the contact arm and the pole pieces 9 and 11 by adjustment of the set screw 16 or by varying the tension of the spring 7 to vary the force opposing attraction of arm 1. With the coil 5 formed as illustrated the size thereof may be readily varied by removal of the desired number of washers, the varying thickness of the washers enabling a num-

ber of variations exceeding the number of washers.

While the switch illustrated is designed and adjusted to respond only at frequencies below a predetermined limit it is obvious that a switch embodying the same elements and principles might be made to respond only when the frequency of the current supplied thereto exceeds a given limit. Also 10 various other modifications of the switch are possible without departing from the scope of the appended claims.

What I claim as new and desire to secure by Letters Patent is:

15 1. In an electric switch, in combination a movable contact member, electromagnetic means to be supplied with an undulating current to produce a magnetic flux for op-

erating said member and a coil threaded by such magnetic flux to produce an opposing magnetic flux rendering said means inoperative to actuate said member while the frequency of the current supplied thereto exceeds a given limit, said coil comprising a plurality of washers of varying thickness. 20 25

2. In an electric switch in combination a movable contact member an electromagnet having parallel magnetic circuits whereby the magnetic flux thereof produces opposing pulls on said member and a damping coil 30 threaded by the flux which tends to move said member, said coil comprising a plurality of washers of varying thickness.

In witness whereof, I have hereunto subscribed my name.

HENRY N. WADE.
